UNITED STATES PATENT OFFICE.

WILLIAM HARPER DAY, OF HOUNSLOW, ENGLAND.

MACHINE FOR MAKING CANDLES.

SPECIFICATION forming part of Letters Patent No. 694,093, dated February 25, 1902.

Application filed July 12, 1900. Serial No. 23,373. (No model.)

To all whom it may concern:

Be it known that I, WILLIAM HARPER DAY, a subject of the Queen of Great Britain, and a resident of Hounslow, in the county of Middlesex, England, have invented certain new and useful Improvements in Machines for the Manufacture of Candles, (for which I have applied for a patent in Great Britain, No. 1,770, dated January 27, 1900,) of which the following is a full, clear, and exact specification thereof.

This invention consists of improvements in or relating to candle-making machines, the object being to enable candles to be readily removed after being passed out of the mold and providing the mold with greater conductivity without unnecessarily reducing the strength and also a means of cleaning the outside of said molds.

For purposes of illustration I will now refer to the annexed drawings, in which—

Figure 1 is a sectional side elevation showing my invention applied to a candle-making machine; Fig. 2, a plan view of machine with lifter removed; Fig. 3, a sectional view, to enlarged scale, of mold; Fig. 4, a view, to enlarged scale, of my lifter or clamp, a section being taken through line X Y, Fig. 5; Fig. 5, a plan view of Fig. 4.

The lifter is formed in two parts *a* and *b*. Upon the candles entering the holes *c* in part *a*, first passing through holes *d* in part *b*, the latter is moved out of alignment with part *a* by means of the handle *e*, thus gripping the candles. The lifter carrying the candles may then be removed from the machine. The alignment of parts *a* and *b* is insured by a catch *f*, engaging in notch *g*, *h* being a handle for operating same when desired.

The molds *i* are formed of any suitable material and may be incased in a sheath or coil of wire *j*, which may be either embedded with the substance of the mold or wound upon the outside thereof, copper wire being employed

on account of its good conductivity to prevent the molds from bursting, *k* being a casing of any suitable material. This mold is employed in any convenient form of machine in which plungers or pistons are employed for forcing the candle from the mold. The cleaning is effected by causing the plate *j*, having suitable sliding surfaces, to travel or engage upon

the outside of the molds *i*, thus removing the undesired substance deposited by the water introduced into the jacket or chamber *j* for the purpose of cooling the molds, and which in many cases contains a surplus of foreign matter. The bearing-surfaces upon this plate may be of any convenient substance or construction, and the up-and-down movement of the cleaning-plate may be effected by attaching it to the plate *k*, carrying the hollow pistons *k*², said plate *k* being raised and lowered by the fixed pinion *m*, engaging on rack *n*, attached to plate *k*. The cleaner is moved by the plate *k* coming into contact with nuts *o* and *o'* or the plate *j* may, if desired, be independently raised or lowered, as will be readily understood.

The whole operation is as follows: The wicks *l*, carried by the reels *2*, are passed through the hollow pistons *k*² and through the molds and are laid over the tops thereof. The molten wax is then poured into the pans *q*, from thence flowing into the molds. Water is then admitted to the chamber *j* to cool the candles. When set, they are forced from the molds by the pistons *k*², which are operated by the rack *n* and pinion *m*, as afore described, and enter the holes in lifter and are held therein, as shown in Fig. 1, by moving the lower portion *b*. The wicks *l* are then taut and centrally placed in the molds. The molds are again filled, and when the next batch are cooled the wicks are cut at points *3* and the lifter removed with the first batch of candles, which would be "wasters," as the wicks would not be central. The second batch is then removed from the molds and are received and held by the lifter while the next batch are being molded, and so on. It will be seen that the cleaning-plate *j* is operated each time the molds are emptied.

Having thus described my invention, what I claim, and desire to secure by Letters Patent, is—

In candle-making machines, the combination of a mold consisting of a suitable material in which a sheath or coil or winding of wire is embedded or wound upon the outer surface, a sliding plate or cleaner adapted to remove the undesired substance from the exterior of the mold, a lifter or clamp consisting of a block having apertures therein to grip

the candles as they are removed from the mold which is effected by moving a sliding plate having similar apertures to the block aforesaid so that the apertures in each are 5 out of axial alinement, a locking device for the purpose of maintaining the sliding plate in the desired position.

In testimony that I claim the foregoing I have hereunto set my hand this 2d day of April, 1900.

WILLIAM HARPER DAY.

Witnesses:

BENJAMIN CLARK,

WILLIAM JOHN WEEKS.
